DRIVING MECHANISM FOR STOKERS

John Van Brunt, Flushing, N. Y., assignor to International Combustion Engineering Corporation, New York, N. Y., a corporation of Delaware

Application December 2, 1931, Serial No. 578,518

9 Claims. (Cl. 74—26)

This invention relates to driving mechanisms for stokers.

One of the primary objects of my invention is the provision of a drive for stokers of a character such that an inexpensive motor may be employed.

More particularly it is an object of my invention to provide a simple and effective way by which the stroke of the reciprocating portions of a stoker may be varied at will to suit varying operating conditions, even though a constant speed prime mover device be employed.

More specifically my invention contemplates the provision of the improved features and combinations of parts hereinafter more fully pointed out.

How the foregoing, together with such other objects and advantages as may hereinafter appear or are incident to my invention are realized, is illustrated in preferred form in the accompanying drawings, wherein:

Figure 1 is in part a side elevational view and in part a sectional elevational view showing a stoker constructed in accordance with my invention applied to a furnace, the lower portion of which is illustrated in section;

Figure 2 is a cross section taken in substantial part on the line 2—2 of Figure 1, but with the right-hand grate and associated tuyère construction shown in section taken on the line 2a—2a of Figure 1;

Figure 3 is an enlarged longitudinal section of the left-hand portion of Figure 1;

Figure 4 is a plan view of the left-hand portion of Figure 1;

Figure 5 is an enlarged front view of a selector and controlling device which I employ, with the upper portion of the casing structure in section to more clearly show certain of the interior parts;

Figure 6 is a side view of Figure 5, with the upper portion of the casing structure in section;

Figure 7 is a plan view of Figure 5, with the cover removed, and

Figures 8 and 9 are detail views illustrating a cam assembly which I employ.

The particular stoker illustrated is of the single retort, underfeed, lateral overfeed type and comprises in general a coal hopper A, a feeder box B, a feeding device indicated as a whole by the reference letter C, a retort D, a wind box E, tuyères F at each side of the retort, and side grates G below which an ashpit is located. The stoker may be applied to various types of furnaces, such as the furnace H illustrated in Figure 1. Air is led to

the wind box E from a fan E' by means of a duct E''.

The feeder device C comprises a reciprocating plate or sliding bottom 9 having a pusher block or ram 10 mounted thereon at the hopper end (see Fig. 3) and auxiliary pushers or rams 11 and 12 located at intervals therealong. When the feeder device is reciprocated, coal is fed from the hopper A through the feeder box B and into the retort D by means of the pusher block 10, which, with each forward movement of the bottom 9, pushes a charge of coal into the retort. The auxiliary pushers aid in the distribution of the fuel from the front to the rear of the retort. The amount of coal fed to the retort depends upon the reciprocations of the sliding bottom, and the mechanism which I employ to vary the feed will be described fully hereinafter.

In operation, the coal remains in the retort for a period of time during which it passes through a coking process and as it nears the top of the fire it becomes incandescent. At this point the tuyères admit a forced blast of air from the wind box to burn the fuel. Combustion of any unburned fuel is completed on the adjoining side grates G which are provided with shaking mechanism as indicated at 13 in Figure 2.

The feeder device C is adapted to be reciprocated by means of driving mechanism indicated as a whole by the reference letter J and comprising in general a constant speed motor 14, a reciprocating driving member or operating block 15 adapted to be reciprocated with constant length and speed of stroke, by means of a crank shaft 16 to which it is connected by a connecting rod 17, the operating block 15 being suitably guided in slots 18 provided in the side walls of the feeder box structure B.

Gear reduction mechanism K is located between the motor and the crank shaft and comprises in general reduction gearing 19 of any conventional type, having a driving shaft 20 adapted to receive its drive from the motor by means of a chain drive 21 and having its final driven gear 22 mounted on the crank shaft 16. Thus the constant speed motor 14 drives the crank shaft at reduced speed and the crank shaft imparts continuous reciprocatory movement to the operating block or driving member 15. It is pointed out, however, that the driving member 15 is not in driving connection with the sliding bottom 9 at all times, for I have provided mechanism which is adapted to establish driving connection between the driving mechanism and the feeding device only at predetermined intervals and, therefore,

the driving member 15 runs at times in idle cam *i*, which is provided with eight cam lobes *i'*.
stroke.

The mechanism referred to includes a latch device 23 having a movable latch member or pawl 24 pivotally carried by the sliding bottom 9 by means of a rock pin 25 and a fixed latch member 26 carried by the operating block or driving member 15; and a selector and controlling device indicated as a whole by the reference letter L 10 adapted to actuate the latch device.

Before describing the device L in detail, it is pointed out that when the latch device is in its latching position, as illustrated in Figure 3, the latch member 24 hooks over the latch member 26, 15 thus connecting the driving member 15 to the sliding bottom 9. The device L is so timed and the latch device so located that it is actuated to its latching position when the crank arm of the crank 19 and the driving member 15 are in their 20 extreme forward positions, so that as the crank continues to rotate, the sliding bottom is pulled in its back or outward stroke by virtue of the latch connection. In order to prevent unlatching of the latch device in this movement, I have inclined 25 the latch engaging surfaces so as to obtain a wedge action.

It will thus be seen that the device L which controls the latch device need only hold the latch member 24 in its downward position for a very 30 short time, because the latch member cannot disengage while the crank is pulling the driving member to the left, i. e., in its outward or backward stroke. As soon as the driving member 15 begins its inward or forward stroke, the latch member 24 is raised out of contact with the latch member 26 as by means of a counterweighted lever 27 secured to the rock pin 25. The member 24 will remain in its unlatched position until it is again moved to its latching position by the 40 device L. On the inward stroke, the driving member 15 also moves the sliding bottom 9 inwardly, contact being made between an abutment 28 on the sliding bottom and the end surface 29 of the member 15, although on this inward stroke the driving device is not connected to the feeding device other than by abutment contact. Therefore, with the latch device in unlatched position, the driving member 15 is free to reciprocate back and forth in idle stroke until 45 the latch device is next moved into its latching position.

The selector and controlling device L above referred to comprises in general a casing 30 having bearings 31 for a cam shaft 32, a plurality of cams 33 secured on the cam shaft 32, and a lever 34 adapted to be actuated by the cams. The lever 34 is pivoted in the casing at 35 and carries a roller rod 36 at its inner end and a projecting arm 37 at its outer end. A cam roller 38 is slidably and rotatably mounted on the rod 36. The cam roller 38 is adapted to be moved lengthwise of the rod by means of a forked shifter member 39 which is slidably mounted on a rod 40 supported by the casing 30 in parallel 60 spaced relation to the roller rod 36.

In this instance I have illustrated nine cams 33 as being mounted on the cam shaft 32 to rotate therewith and the first cam *a* starting from the left of Figures 5 and 8 is blank, i. e., the cam 70 surface thereof with which the cam roller 38 is adapted to contact is concentric with the axis of the cam shaft. The second cam *b* is provided with one cam lobe or tooth *b'*, the third cam *c* with two cam lobes *c'*, the fourth cam *d* with 75 three cam lobes *d'*, and so on up to the ninth

the driving member 15 runs at times in idle cam *i*, which is provided with eight cam lobes *i'*.
stroke.

The cam roller 38 with its shifter member 39 is adapted to be moved in a direction longitudinally of the casing by means of a shifter arm 41 secured on a rock shaft 42 at its lower end, and having a forked upper end 43 adapted to straddle a pin 44 carried by the shifter member. The shaft 42 is mounted to rock in a bearing 45 at the lower portion of the casing 30 and has secured to its outer end an arm or shifter lever 46. 80 85

The shifter lever 46 and shifter arm 41 are adapted, when actuated, to move the cam roller 38 into registry with any one of the plurality of selector cams provided on the cam shaft. In Figure 5 the shifter mechanism is shown in a position such that the cam roller 38 engages the blank cam *a* and therefore, when the cam rotates, no movement is imparted to the lever 34. An arcuate pad 47 is provided on the side of the casing at which the shifter lever 46 is mounted 90 and is provided with a plurality of holes 48 corresponding in number and spacing to the number of cams employed. An upwardly projecting arm 49 is provided on the shifter lever 46 which arm carries a pin 50 adapted to be inserted in a 95 hole 48 corresponding to the particular cam selected for operation. This pin not only holds the shifter mechanism against unintended displacement, but also gives an indication as to which cam has been selected for operation. The pin may be attached to the arm 49 as by means of a chain 51, such as illustrated in Figures 5 and 6, to prevent its being lost.

In the event that automatic control is desired, the shifter lever 46 may be automatically 110 operated by connecting it to any suitable form of automatic regulating device as by means of a cable 46a. In such instances, the pin 50 would be removed and a counterweight 46b would be applied to the lever 46. 115

The cams are rotated by means of a sprocket wheel 52 secured on the cam shaft 32 and receiving its drive from the crank shaft 16 through the medium of a gear 53 secured on the crank shaft, a gear 54 meshing therewith, a sprocket 120 wheel 55 mounted on the shaft of the gear 54 and a chain 56 drivingly connecting the sprockets 55 and 52. It will thus be seen that since the motor 14 drives the crank shaft at constant speed, the selector cams 33 will also be driven at 125 constant speed. The speed ratio in this instance is such that the cam shaft 32 rotates at one-eighth of the speed of the crank shaft, although it is to be understood that the speed change as between the crank shaft and the cam shaft is 130 determined by the number of cams and cam lobes employed in the selector mechanism.

A plunger 57 is mounted in a support 58 secured to the side of the feeder box structure in such location with respect to the selector and controlling device L that the under surface of the arm 37 of the cam operated lever 34 engages the upper rounded end of the plunger. The plunger is maintained in engagement with the arm 37 by means of a spring 59 and a roller 60 140 is carried at the lower end of the plunger. The roller 60 contacts with an arm 61 of the counterweighted lever 27 above referred to, and when the plunger is depressed the arm 61 is moved downwardly so as to rock the rock shaft 25 in 145 a direction to cause engagement of the latch member 24 with the latch member 23. The plunger is moved into its depressed position when the lever 34 is actuated by a cam lobe and is spring returned to its non-depressed position 150

when the cam roller 38 leaves a cam lobe, and rides on the concentric portion of the cams. When the plunger moves to its non-depressed position, the rock shaft 25 is free to rock in a direction to cause latch disengagement under influence of the weighted lever 27, although as above pointed out, such latch disengagement does not take place until the driving member 15 has reached the end of its outward stroke and 10 starts on its inward or forward stroke. In Figure 1 the parts just described are illustrated in the position they assume when the latch mechanism is being actuated by a cam lobe of one of the cams of the selector device L.

15 The cams 33 are so timed that latch engagement takes place at the end of an inward or forward stroke of the operating member 15, and therefore, when the shifter mechanism of the selector device is moved to its position for selecting the cam b, for example, the latch will be moved to latching position when the single cam lobe b' of the cam operates on the lever 34 to actuate the plunger 57. As soon as the cam lobe has passed the cam roller, the plunger returns 20 to its non-depressed position and remains in such position until the cam lobe again actuates the lever 34, such actuation taking place once in eight back and forth reciprocations of the driving member 15. The operation is similar for 25 the cam c, except that the lobe is moved to latching position twice in eight complete back and forth reciprocations of the driving member 15 and so on for all of the cams up to the last cam i which actuates the latch device once for each 30 complete back and forth reciprocation of the driving member.

35 In the particular arrangement disclosed, speed variations from one to one to eight to one may be obtained, although it is to be understood that with additional cams and suitable change of ratio between the cam shaft and the crank shaft, greater variation may be obtained.

40 It will be seen from the foregoing that I have provided a driving mechanism for stokers by 45 which the stroke of the reciprocating portions of a stoker, such for example as a reciprocating feeder device, may be carried at will to suit variable operating conditions while employing an inexpensive constant speed driving motor, for I 50 am enabled through the use of the selector and controlling mechanism to cause the reciprocating feeder to feed coal intermittently at predetermined and variable intervals, according to the 55 selection made, even though the mechanism for driving the feeder be running continuously. While I thus vary the coal feed, the length and speed of the feed stroke is nevertheless constant so that proper fuel bed conditions are insured at all loads. The arrangement is also such that 60 a single driving motor operates the feeder device, the selector and controlling device, and the fan E'. Furthermore, the arrangement permits of supplying air to the stoker without feeding coal even though the fan and feeder device are driven 65 from the same motor. The device is simple in design, of rugged construction, and requires minimum aisle space.

I claim:—

1. A driving device comprising a reciprocating 70 driving member, a driven member adapted for reciprocation, and selectively controllable means for rendering idle certain of the strokes of the driving member, for connecting the driving member to the driven member so as to render the remaining strokes driving, and for connecting said

members so as to render all of the strokes driving.

2. A driving device comprising a reciprocating driving member, a driven member adapted for reciprocation, means for releasably connecting said members together, and selective mechanism 80 for actuating said means to connect said members for reciprocation together in every reciprocation of the driving member or to connect said members in only certain reciprocations of a cycle and to disconnect the members in the remaining reciprocations of the cycle. 85

3. A driving device comprising a reciprocating driving member having a set stroke, a driven member adapted for reciprocation, means for releasably connecting said members for reciprocation together in said set stroke, and selective mechanism having a selector member for effecting such connection for certain of the strokes of the driving member, and a selector member for effecting such connection for every stroke of the 90 driving member. 95

4. A driving device comprising a constant speed reciprocating driving member, a driven member adapted for reciprocation, means for releasably connecting said driving member to 100 said driven member, actuating means for said connecting means, and a selector device operatively associated with said actuating means for governing the actuation of the connecting means including a plurality of movable members, means for moving said members, and selector members carried by said movable members for controlling the operation of the actuating means, one of said selector members being adapted to effect control whereby the driving member is connected to the driven member in all of its strokes. 105

5. A driving device comprising a driving member adapted to run in driving and idle strokes, a driven member adapted to be variably driven by said driving member, a plurality of cam members with varying cam surfaces, means actuated by said cam members for controlling said strokes, and means for selecting any one of said cam members to actuate said means, one of said cam members having cam surfaces arranged to render all of the strokes of the driving member driving. 115

6. A driving device comprising a constant speed motor, a driving member driven by said motor at constant speed, a driven member, means for connecting and disconnecting said driving and driven members, an actuating member for said means, a plurality of cams the cam surfaces of which differ from each other, means for driving said cams at constant speed, and means for moving said actuating member into position for operation by any one of said cams. 120

7. A driving device comprising a constant speed driving motor, a reciprocable driving member, a reciprocable driven member, means for imparting reciprocating movement to said driving member from said motor, normally unlatched latch means associated with the driving and driven members, means for latching said latch means to connect said driving and driven members for reciprocation together in the same length of stroke, including an actuating member and selective cams controlling the actuating member. 125

8. A driving device comprising a constant speed driving motor, a reciprocable driving member, a reciprocable driven member, means for imparting reciprocating movement to said driving member from said motor, normally unlatched latch means associated with the driving and driven members, means for latching said latch, means to connect said driving and driven mem- 130

bers for reciprocation together in the same length of stroke, including an actuating member, and a plurality of rotatable cam members for controlling the actuating member, one of which has a concentric cam surface, another one cam lobe, another two, another three, and so on, and means for selecting one of said cam members to operate said actuating member.

9. A driving device comprising a constant speed driving motor, a reciprocable driving member, a reciprocable driven member, means for impart-

ing reciprocatory movement to the driving member from said motor, latch means for connecting said driven member to and for disconnecting it from said driven member, a plurality of rotatable cams with varying number of cam lobes, means for driving said cams at constant speed, and means for actuating said latch means including a member shiftable into operative relation with any one of said cams.
